CLAIM

The ornamental design for a cat litter mat as shown and described.

DESCRIPTION

FIG. 1 is a perspective view of a cat litter mat showing our new design;

FIG. 2 is another perspective view thereof;

FIG. 3 is a front elevational view thereof;

FIG. 4 is a rear elevational view thereof;

FIG. 5 is a left side elevational view thereof, the right side elevational view being a mirror image of FIG. 5 and therefore not shown;

FIG. 6 is a top plan view thereof;

FIG. 7 is a bottom plan view thereof;

FIG. 8 is an exploded perspective view of the cat litter mat;

FIG. 9 is an enlarged view of portion 9 shown in FIG. 1; and, FIG. 10 is an enlarged view of portion 10 shown in FIG. 2. The dash-dash broken lines in the drawings depict portions of the cat litter mat that form no part of the claimed design. The dot-dash broken lines are for the purpose of annotating the enlarged portions only and form no part of the claimed design.

1 Claim, 10 Drawing Sheets
